SEAT STRUCTURE

Marcella J. Strand, Lansing, Ill.

Application March 9, 1953, Serial No. 341,140

7 Claims. (Cl. 155—79)

1

This invention relates to a novel construction of child's seat for use either with conventional straight back chairs, vehicle seats or upholstered chairs and which is adapted to be detachably suspended from the back rest.

More particularly, it is an aim of the present invention to provide a seat structure which will open automatically for applying a child thereto or for removing a child therefrom and wherein the weight of the child on the seat will retain a guard portion thereof in a closed position around the torso of the child.

Another object of the invention is to provide a seat structure which is so constructed that when applied to the upwardly and rearwardly inclined back rest of a chair that the child may not overturn the chair backward by pushing against a table or other structure immediately adjacent the front of the chair.

Various other objects and advantages of the invention will hereinafter become more fully apparent from the following description of the drawings, illustrating a presently preferred embodiment thereof, and wherein:

Figure 1 is a side elevational view showing the chair as it would appear when supporting a child;

Figure 2 is a front elevational view thereof looking from left to right of Figure 1;

Figure 3 is an enlarged horizontal sectional view, partly in top plan, taken substantially along a plane as indicated by the line 3—3 of Figure 2;

Figure 4 is an enlarged horizontal sectional view taken substantially along a plane as indicated by the line 4—4 of Figure 1; and

Figures 5 and 6 are enlarged vertical sectional views taken substantially along planes as indicated by the lines 5—5 and 6—6, respectively, of Figure 3.

Referring more specifically to the drawings, the novel child's seat in its entirety is designated generally 8 and includes a panel-like member forming a back rest 9. A panel-like member forming a seat 10 is hingedly mounted along a back edge thereof to the bottom edge of the back rest 9 by means of looped strap members 11 and 12 portions of which are secured by fastenings 13 to the back rest 9 and seat 10, respectively. Curled end portions of said strap members 11 and 12 provide aligned loops or hinged barrels 14 through which extends a pintle or hinged pin 15 for mounting the seat 10 for vertical swinging movement upwardly toward the back rest 9 or downwardly away from said back rest.

A pair of corresponding guard members 16 are hingedly connected to the back rest 9, adjacent

the side edges thereof and above the seat 10. Each of said guard members 16 includes a vertical side wall portion 17 to a rear edge of which hinge leaves 18 are secured by additional fastenings 13. Similar hinge leaves 19 are secured by fastenings 13 to the back rest 9 and said hinge leaves 18 and 19 are provided with aligned hinge barrels 20 through which extend hinge pins or pintles 21 for swingably mounting the guard members 16 on the back rest 9 for swinging movement outwardly away from one another or inwardly toward one another. The wall portions 17 at their upper edges are provided with outwardly extending flanges forming arm rests 22. The wall portions 17 are recessed at their bottom edges at points spaced outwardly from their inner hinged edges to provide narrower guard elements 23 which are curved inwardly intermediate of their ends to provide front guard portions 24 which extend toward one another and which terminate in spaced apart relationship, as illustrated in Figures 2 and 3, when the wall portions 17 are disposed substantially parallel.

The seat pintle 15 supports coil springs 25 the ends of which bear against the back rest 9 and the underside of the seat 10 for urging the seat to swing upwardly toward said back rest. The pintles 21 of the guard members 16 likewise mount coil springs 26 the ends of which bear against the back rest 9 and the inner sides of the walls 17 for urging the guard members 16 to swing outwardly and away from one another, as best illustrated in Figure 4.

The wall portions 17 of the guard members 16 are connected to the seat 10 by flexible members such as chains 27. Other flexible members, such as the chains 28, are connected to the back rest 9 and seat 10 at points spaced from the seat hinge 14, 15.

The seat 10 is provided with a removable disk-like section 29 which is supported in an opening 30 thereof by strap members 31 which are rigid and which are secured to the upper side of the disk 29 and have outer ends overlying a portion of the upper side of the seat 10 which surrounds the opening 30. The disk 29 can be removed so that the opening 30 can be employed with a receptacle disposed therebeneath as a toilet seat. A horn member 32 has a base portion 33 which is disposed on the seat 10 between its forward edge and the opening 30 and which is secured thereto by a fastening 34. The horn 32 extends upwardly from the seat 10 and is curved forwardly away from the back rest 9.

A secondary or rear back member or panel 35

is disposed behind the back rest 9 and is held spaced therefrom by vertical side walls 36 and a bottom wall 37 which combine with the back rest 9 and rear wall 35 to form an elongated box-like receptacle 38 having an open top which is normally closed by a cover 39 which is hinged at 40 to the upper end of the rear wall 35, for swinging movement upwardly and rearwardly away from the back rest 9 toward an open position. The back rest 9 extends to above the container or receptacle 38 and the upper portion thereof is provided with an opening to form a handhold 41 by means of which the seat structure 8 may be manually supported and carried conveniently. Metal strap members 42 are secured by fastenings 43 each to the back rest 9, rear wall 35 and one side wall 36 for reinforcing the receptacle 38.

A pair of double hooks 44 are swingably mounted on the receptacle 38 externally of the walls 36 by means of pivot pins 45 which extend inwardly through intermediate shank portions 46 of the hook members 44 and which pivot pins are anchored in said side walls 36 and in upper strap members 42 thereof. A spacing member 47 is mounted on each pivot pin 45 between the adjacent strap member 42 and shank portion 46 for spacing the hook members 44 outwardly from the walls 36. Each hook member has a short hook 48 constituting one end thereof and an extension of one end of the shank 46 and a long larger hook 49 constituting the other end thereof and an extension of the other end of the shank 46.

Assuming that the hooks 48 are disposed in uppermost positions, as illustrated in Figures 1 and 2, said hooks may be engaged over the upper edge of the back rest of a straight chair for supporting the seat 8 on the front side thereof and with the rear wall member 35 engaging against the front side of the chair back rest, not shown. The seat member 10 will be supported at an incline upwardly and outwardly with respect to the back rest 9 by its springs 25 and the guard members 16 will be displaced outwardly from their positions of Figure 3 by the springs 26 and to the limit as permitted by the chains 27, so that the guard members 16 will be spread to enable a child to be readily placed therebetween and on the seat member 10 and with the legs straddling the horn 32. The weight of the child on the seat member 10 will cause said seat member to swing downwardly to a position substantially at a right angle to the back rest 9 and in which position it is supported by the flexible members or chains 28. This downward swinging movement of the seat member 10 will cause the flexible members 27 to pull the guard members 16 inwardly to position the walls 17 thereof substantially parallel, as illustrated in Figures 2 and 3 and so that the guard members 16 will substantially surround the torso of the child. So long as the weight of the child is on the seat member 10 it cannot swing the guard members 16 away from one another and is thus confined within the seat 8. The legs of the child extend outwardly from either side of the horn 32 and beneath the guard member extensions 23. However, by merely lifting upwardly on the child to remove its weight from the seat member 10, the guard members 16 will be swung apart so that the child can be readily removed from the seat 8. The back wall 35 is spaced a substantial distance behind the back rest 9 and seat 10 so that the weight of the child is spaced forwardly from the chair back rest on which the seat 8 is suspended thus preventing a child from

pushing against a table or a similar structure and overturning a chair backwards on which the seat member 8 is supported.

The hook members 44 may be swung on their pivots 45 through arcs of 180° approximately to position the hook elements 49 in uppermost positions for engagement over the upper edge of the back rest of an automobile seat or a piece of upholstered furniture for similarly supporting a child's seat 8 on the front thereof. A child is applied to and removed from the seat 8 when applied to a vehicle seat back rest or to the back rest of an upholstered piece of furniture, in the same manner as previously described.

Where the seat 8 is used by older children who can support their weight on a chair or vehicle seat for spreading the guard members 16, a latch is provided for detachably connecting the guard portions 24. Said latch comprises a bar 50 which is swingably connected adjacent one end thereof by a fastening 51 to the outer side of one of the guard portions 24. A keeper 52 is anchored in and extends outwardly from the outer side of the other guard portion 24 and includes an outwardly

extending stem having a head at its outer end. The bar 50, near its free end, is provided with a keeper receiving notch 53, as best illustrated in Figure 5, having one end opening outwardly of the bottom edge of the latch bar 50 and an outwardly offset closed opposite end through which the stem of the keeper 52 extends. Thus, to release the latch bar 50, the guard members 16

must be swung slightly toward one another after the latch bar 50 has been swung upwardly to disengage the keeper 52 from the upper closed end of the notch 53 and so that the keeper 52 can be aligned with the open lower end of the notch 53 to permit the latch bar 50 to then be swung upwardly to a released position. A child seated on the seat member 10 would be unable to accomplish these successively operations necessary to release the latch bar 50 and is thus retained in the seat member 3.

The receptacle 38 may be used for any suitable purpose as for example in storing diapers or other articles for use by a young child.

Various modifications and changes are contemplated and may obviously be resorted to, without departing from the spirit or scope of the invention as hereinafter defined by the appended claims.

I claim as my invention:

1. A child's seat structure comprising a back rest, means connected to said back rest including chair or seat back engaging hooks for suspending the child's seat structure on the back rest of a chair or seat, a seat having an inner edge hingedly connected to the back rest near a lower end of said back rest for vertical swinging movement, guard members having inner ends hingedly connected to said back rest above said seat and adjacent the side edges of the back rest for horizontal swinging movement about vertical axes, said guard members having inturned outer free end portions extending toward one another, means limiting downward swinging movement of the seat relative to the back rest, and means connecting each of the guard members to the seat for swinging the guard members toward one another when the seat is swung downwardly.

2. A child's seat structure as in claim 1, and spring means urging said guard members to swing away from one another toward outwardly diverging positions and for drawing said seat upwardly.

3. A child's seat structure as in claim 2, said

guard members including vertical wall portions maintained in substantially parallel relationship to one another by said springs and seat when a weight is supported on the seat, and said inturned outer free end portions having bottom edges upwardly offset from the bottom edges of said wall portions for accommodating the legs of a child between said inturned end portions and the seat.

4. A child's seat structure as in claim 1, spring means urging said guard members to swing away from one another, and latch means releasably connecting the inturned outer end portions of the guard members including a latch bar having a keeper receiving slot provided with offset open and closed ends whereby swinging movement of the guard members is required for disengaging the latch bar from the keeper.

5. A child's seat structure as in claim 1, said means connected to said back rest and provided with supporting hooks including a rear wall connected to the back rest and spaced from the side thereof opposite to the side on which the seat is supported, said rear wall being adapted to engage against the forward side of the chair or seat back rest on which the child's seat structure is suspended for spacing the child's seat structure back rest therefrom.

6. A child's seat structure of the type adapted to be suspended on a chair or seat back rest including a back rest and a seat member hingedly connected to a forward side of said back rest for vertical swinging movement between a raised

position and a lowered position in which lowered position the seat member is disposed at a greater angle to the back rest than in the raised position thereof, a pair of guard members hingedly connected to said back rest above the level of the seat member hinge for swinging movement in horizontal planes about vertical axes toward and away from one another, spring means urging said guard members outwardly of one another, and means connecting the guard members and seat whereby the seat is swung upwardly by outward swinging movement of said guard members and said guard members are swung toward one another by downward swinging movement of the seat member when a weight is placed thereon for positioning the guard members in positions substantially surrounding the seat member when the seat member is in a lowered position.

7. A child's seat structure as in claim 6, and means forming a stop for limiting downward swinging movement of the seat member.
